UNITED STATES PATENT OFFICE

WALTER C. ASTRUP, OF CLEVELAND, OHIO

DESIGN FOR A CURTAIN-POLE END PIECE

Application filed October 17, 1929. Serial No. 33,074. Term of patent 7 years.

To all whom it may concern:

Be it known that I, WALTER C. ASTRUP, a citizen of the United States of America, residing at Cleveland, in the county of Cuyahoga and State of Ohio, have invented a new, original, and ornamental Design for Curtain-Pole End Piece, of which the following is a specification, reference being had to the accompanying drawing, forming a part thereof.

The figure is a perspective view of a curtain pole end piece, showing my new design.

I claim:

The ornamental design for a curtain pole end piece, as shown.

In testimony whereof I do now affix my signature.

WALTER C. ASTRUP.
